ELECTRODE HOLDER

Philip L. Bourque, Detroit, Mich.

Application January 24, 1944, Serial No. 519,499

4 Claims.

(Cl. 219—8)

The invention relates to electrode holders such as are used in arc welding and it is the object of the invention to obtain a construction which will firmly hold the electrode during the performance of the work while permitting of easily and quickly exchanging electrodes whenever necessary.

It is a further object to obtain a construction of holder in which the handle portion is free from any projections which might interfere with freedom of movement thereof.

Still further it is an object of the invention to obtain a construction in which a relatively small angular movement or rotation of the handle is all that is required for releasing or clamping the electrode. With these and other objects in view the invention consists in the construction as hereinafter set forth.

In the drawing:

Fig. 1 is a central longitudinal section through my improved electrode holder;

Fig. 2 is a similar view showing the clamping jaws in released position for engagement or disengagement of the electrode;

Fig. 3 is a section on line 3—3, Fig. 2, showing in full and dotted lines the clamped and released positions of the jaws and the degree of angular movement between the same;

Fig. 4 is a view similar to Fig. 1 showing a modified construction; and

Fig. 5 is an elevation of the multiple thread screw for effecting the clamping or releasing of the jaws.

As illustrated in Fig. 1, A is a tubular handle formed of suitable dielectric material. B is a metallic supporting sleeve within the handle A and C is a socket member secured within the sleeve B for receiving the conductor cable (not shown). Fixed to and preferably integral with the socket C is a male screw threaded member D for engaging a correspondingly threaded female member E, the latter revolvably engaging the sleeve B. The member E has attached thereto a pair of resilient arms F which extend outward through the end of the handle and terminate in clamping jaw members F'. The arms F are biased to hold the jaws in clamped position and between the jaw portions of the arms and the portions thereof engaging the member E are obliquely inclined cam portions F². The male member D has a forwardly extending portion D' terminating in a ball member D² which latter is arranged between the portions F² so that by rotating the handle in one direction relative to the jaws, the ball D² will be forced between the cam portions F² to spread the jaws and release their clamping

engagement. On the other hand, a rotation of the handle in the opposite direction will withdraw the ball D² permitting the clamping of the jaws by the inherent resiliency of the arms F.

5 The jaws F' are preferably formed with a series of notches F³ in one member thereof for engaging the electrode. They are also provided with a larger notch F⁴ for receiving an electrode when the jaws are in clamped position, which electrode 10 may be used as a lever for turning the jaws relative to the handle and ball D² to effect a releasing of the clamp. Thus, as shown, the notch F⁴ is formed by U-shaped bends in the jaws. The jaws F' are externally insulated by pads G of insulating material which are secured to the jaws by screws G'.

With certain constructions heretofore used, the jaws for clamping the electrode are operated by a lever pivotally connected to the handle and 20 projecting outward therefrom. This is objectionable inasmuch as any projection from the handle will interfere with its freedom of movement and may catch on some obstruction. With my improved holder there are no projections from either 25 the handle or the jaws and the operating mechanism for the jaws is completely housed and sealed within the handle. It is desirable to effect the clamping or releasing of the jaws by a relatively small degree of angular movement or rotation of the handle. This, I accomplish by using a relatively steep-pitched screw which will provide the necessary axial movement by a small angular movement. However, it is equally essential that 30 when the electrode is clamped by the jaws it should be held from accidental release and with a steep-pitched screw there is greater tendency for movement towards releasing position. I, therefore, have designed the screw with a multiple thread thereby increasing frictional resistance 35 to releasing movement. This is illustrated in Fig. 5 where the member D has parallel threads D³, D⁴, D⁵ between successive convolutions. The member E is correspondingly threaded and, consequently, the friction between these two members will be sufficient to always hold the jaws in clamped position against any tendency towards 40 automatic release.

Fig. 4 illustrates a modified construction in which there is provided a circular handle H of a 45 diameter larger than the handle A arranged at the forward end thereof. This handle H has a hub H' which has a threaded engagement with the interior of the sleeve B, the thread being the opposite hand to that of the thread of the member D. Thus, if the member D has a right hand

thread, the hub H' would have a left hand thread. This hub is also attached by a screw H² to one of the arms F, the arrangement being such that when the handles H and A are relatively rotated the axial movement of the ball F² relative to the jaws F' is the sum of the movements imparted thereto by the screw threads of the hub H' and the member D. In other words, the axial movement is twice that which would be produced by one thread alone. Thus, less relative angular or rotative movement is required with this construction than with the construction shown in Fig. 1 if the pitch of the threads is the same in each case.

Another feature shown in the construction, Fig. 4, is that an air space B' is formed between the handle A and the sleeve B by spacers B². This permits the circulation of air between the tubular handle and the sleeve to dissipate any heat communicated to the latter from the jaws.

What I claim as my invention is:

1. An electrode holder comprising a tubular handle formed of dielectric material, a metallic sleeve within said handle secured thereto, a socket member secured within said sleeve for connection with the conductor cable, a male screw-threaded member projecting forward from said socket, a female screw-threaded member engaging said male member and revolvably engaging said sleeve, a pair of resilient arms secured to said female member and projecting outward from said handle terminating in clamping jaws, said arms being biased towards clamping position and having obliquely inclined cam portions between said jaws and said female member, and a member secured to and projecting from said male member for engaging said cams to spread said arms upon a relative rotation of said jaws and handle.

2. An electrode holder comprising a tubular handle formed of dielectric material, a sleeve member within said tubular handle, a socket member secured within said sleeve member and adapted for connection with the conductor cable, a male screw-threaded member projecting forward from said socket, a female screw-threaded member engaging said male member and slideable within said sleeve, a pair of resilient arms connected to said female member projecting outward from said handle and terminating in clamping jaws, said arms being biased towards the clamping position of said jaws and having obliquely inclined portions between said jaws and said female member, and a member extending forward from said male member having a knob at its outer end for engaging said obliquely in-

clined portions and adapted to be moved forward to spread the same upon a relative rotation of said handle and jaw members, said jaw members being fashioned to provide a notch therebetween of a diameter as great as that of the electrode in the clamped position of the jaws whereby said electrode may be inserted into said notch and used as a lever for rotating the jaws with respect to said holder to release the clamp.

- 10 3. An electrode holder comprising a tubular handle formed of dielectric material, a metallic sleeve within said handle, a socket member secured within said sleeve and serving for connection with the conductor cable, a member fixed to and projecting forward from said socket provided with an externally relatively steep-pitched multiple thread, a member having a corresponding female thread slideable within said sleeve, a pair of resilient arms connected to the latter member projecting forward out of said handle and terminating in clamping jaws, said arms being biased towards clamping position of the jaws and having obliquely inclined portions between said jaws and said female threaded member, and a member projecting forward from said externally threaded member having a knob at its outer end engaging said obliquely inclined portions of said arms whereby a relative rotation of said jaws and handle through a relatively small angle will cause the spreading of said resilient arms and the releasing of the clamp.

- 15 4. An electrode holder comprising a tubular handle, a member slidably fitting within said handle, a pair of resilient arms connected to said member and projecting outward therefrom terminating in electrode clamping jaws, said arms being biased towards clamping position, a screw secured to said handle within the same having a threaded engagement with said member to which 20 the arms are attached, a circular handle of larger diameter than said tubular handle at the forward end of the latter, said circular handle having a hub portion threaded to engage corresponding threads in the interior of said sleeve and being 25 also attached to one of said resilient arms, the threads on said hub and those on the aforesaid screw being of opposite hand, and a member projecting from said screw having a spreading cam 30 engagement with said jaws whereby a relative rotation of said circular handle and tubular handle will axially advance said spreading member an amount equal to the sum of advancement of each of said opposite hand threaded members
